(57) **CLAIM**

The ornamental design for a watering can, as shown and described.

DESCRIPTION

FIG. 1 is a top perspective view of a watering can; FIG. 2 is a top plan view of the watering can shown in FIG. 1;

FIG. 3 is a front elevational view thereof;

FIG. 4 is a rear elevational view thereof;

FIG. 5 is a left side elevational view thereof, with the right side being a mirror image of FIG. 5; and, FIG. 6 is a bottom plan view thereof.

Broken lines showing “**1 1/3 GAL, 1 3/4 GAL, 1 GAL, 1/2 GAL**” illustrate portions of the watering can that form no part of the claimed design.

1 Claim, 3 Drawing Sheets(56)
